UNITED STATES PATENT OFFICE

2,660,791

PAVEMENT MARKER

Albert R. Howell, Los Angeles, and Oscar W. Tackett, San Gabriel, Calif.

Application April 16, 1951, Serial No. 221,223

12 Claims. (Cl. 33—41)

1

This invention is concerned with a pavement marker and it is a general object of the invention to provide a simple, practical, accurate and easily-operated device that can be used to advantage to establish marks or lines on pavements, as where ditches or excavations are to be made.

In practically all communities of appreciable size there are streets or roads provided with pavement and it is common to provide curbs at the longitudinal edges of such pavements. When ditches or cuts are to be made in such pavements for the purpose of installing, replacing, repairing, or otherwise handling equipment such as is required for utilities, water supply, sewage, etc., it is generally practical to locate them relative to a curbing, and when power equipment is to be utilized for the digging of ditches or for the cutting of pavement it is highly desirable that clear and accurate markings be established on the pavements before operations are undertaken.

It is a general object of this invention to provide a pavement marker adapted to be operated relative to or in engagement with a curbing, or the like, and having a marking device serving to establish a satisfactory mark on a pavement as the structure is operated along the pavement in engagement with the curb.

A general object of this invention is to provide a device of the general character referred to wherein the essential or principal elements are adjustable relative to each other, to the end that the structure can be easily, quickly, and accurately set to accommodate or meet various working conditions.

It is another object of the invention to provide apparatus of the general character referred to in which the structure is light, very simple of construction and manufacture, and such that it can be readily handled by a single person in a manner to quickly and accurately establish marks on the pavements.

The structure provided by the invention involves, generally, a frame, preferably a rigid unit made up of an elongate body, preferably tubular in form, a base transverse of the body at the inner end of the body, and braces, preferably tubular, that have their forward or outer ends joined to the body intermediate its ends and joined to the ends of the base. The braces being thus joined to the body leave the body with a free or unobstructed forward end portion and they are preferably tubular and open at their inner ends. A supporting means is provided and involves a plurality of supporting rollers, preferably two, at the inner portion of the frame,

2

and one at the outer portion thereof. In a preferred arrangement there is an inner roller at each end portion of the base or at each corner where a brace joins the base. These rollers are on horizontally disposed axes in planes transverse of the longitudinal axis of the base. The outer supporting roller is on a horizontal axis parallel with the body of the frame. A preferred mounting for the outer supporting roller involves a collar rotatable on the forward end portion of the frame body, means releasably seating the collar on the body, and an arm projecting from the collar and carrying the roller. Through this construction the arm can be rotated or swung to various rotative positions about the longitudinal axis of the frame body to locate the outer supporting roller at various elevations relative to the forward end portion of the frame. A handle is provided and preferably involves spaced handbars each with a shank fixed to the frame, as, for instance, to the body of the frame, and grips at the upper end portions of the shanks. A guide means is provided at the base portion of the frame and preferably involves curb engaging rollers, one at each end of the base of the frame or at each corner where a brace joins an end of the base. The curb engaging rollers are on vertical axes and are preferably carried by stems slidable in the braces and releasably set against movement therein as by set screws. A marker is provided and preferably involves, generally, a marking element and a holder carrying the marking element. A means supports the marker from the frame, preferably for adjustment relative thereto. In a preferred case, the said means involves a rod slidably supported in the frame or entering the frame at the forward end portion thereof so it can be slid or shifted longitudinally of the frame and also rotated within the body of the frame. A releasable means such as a set screw is provided to set the rod in adjusted position. In the preferred arrangement, a collar is provided on the holder of the marker and is rotatable and slidable on the rod, thus providing for adjustment of the marker along the rod as well as about the axis thereof. A releasable means such as a set screw is provided to set the collar of the holder in the desired position on the rod. In a typical situation a single marker is employed, whereas it is contemplated that more than one marker may be used, if desired. In one form of marker, the holder is a tubular carrier supporting an elongate body of chalk yieldingly pressed by a spring. In another form of marker, the marking element is a roller and the roller is

supplied with a marking material such as a fluid by providing a container carrying a supply of fluid and an applicator that receives the material from the container and applies it to the roller.

The various objects and features of my invention will be fully understood from the following detailed description of typical preferred forms and applications of the invention, throughout which description reference is made to the accompanying drawings, in which:

Fig. 1 is a perspective view of a typical form of the invention, showing it in operating position on or over a pavement, and in engagement with the curb at an edge of the pavement. Fig. 2 is an enlarged side elevation of the device. Fig. 3 is an enlarged detailed sectional view taken as indicated by line 3-3 on Fig. 2. Fig. 4 is a detailed sectional view taken as indicated by line 4-4 on Fig. 3. Fig. 5 is an enlarged detailed sectional view taken as indicated by line 5-5 on Fig. 1. Fig. 6 is an enlarged plan view of a portion of the structure taken as indicated by line 6-6 on Fig. 2, and Fig. 7 is a view illustrating a second or modified form of marker, portions thereof being shown in section.

Referring first to the form of the invention illustrated in Figs. 1 to 6 of the drawings, the device involves, generally, a frame A, supporting means B for the frame, a handle C, preferably on the frame, guide means D on the base portion of the frame, a marker E, and means F supporting the marker from the frame.

The frame, in its preferred form, involves a body 10, an elongate base 11, and elongate braces 12. The body 10 is preferably an elongate member, tubular in form, and the base 11 may be an elongate member likewise tubular in form. The inner end of the body 10 is joined or fixed to the base and may be midway between the ends of the base. The braces 12 are preferably elongate tubular members and their outer or forward end portions are fixed to the body 10 at 16, which point is intermediate the ends of the body 10 so that the body has a forwardly projecting portion 17 forward of the braces 12.

The supporting means B preferably involves inner and outer supporting rollers and in a preferred arrangement there are two inner supporting rollers and one outer supporting roller. In the case illustrated there are two inner supporting rollers 20 and they are located at the end portions of the base 11 of the frame, or at the corners where the base connects to the braces 12. In accordance with the invention, the rollers 20 are located below the frame and on horizontal axes in vertical planes normal to the longitudinal axis of base 11. In the case illustrated, each roller 20 is carried by a bracket mounted on or secured to the base 11 of the frame. The bracket shown is U-shaped to partially embrace the base 11 where it is fixed or joined thereto, and it has spaced depending arms 22 between which the roller is located, the roller being carried by a pivot pin 23 that extends between the arms.

The single outer supporting wheel 30 is preferably supported on or from the forwardly projecting portion 17 of body 10 and a preferred form of mounting means involves a collar 31 carried on the body portion 17, an arm 32 projecting from the collar and a pivot 33 carried by the arm and supporting the roller 30. The collar 31 is rotatable and may be shiftable longitudinally on body portion 17 and a suitable means such as a set screw 35 is provided for releasably setting the collar in any suitable position on or around the

body portion 17. Through the mounting means just described, the outer supporting roller 30 can be adjusted to various positions vertically relative to the frame or to the outer end portion of the frame.

The handle C may, in practice, vary widely in form and construction and is preferably a structure carried by the frame A. In the case illustrated, the handle C involves two like elements each involving a shank 40 and a grip 41. The shanks are shown fixed to the body 10 at points spaced apart longitudinally of the body, and they are shown as extending upwardly and somewhat toward the rear side of the structure, so that they carry the grips 41 so that they project toward the side of the device at which the operator is located when the device is being operated, as in the direction indicated by the arrow X in Fig. 1.

The guide means D involves curb engaging rollers 50 and, in a preferred construction, there are two such rollers and these are located at the ends of base 11 of the frame or at the corner where the base 11 joins the braces 12. In accordance with the invention, the curb engaging rollers 50 are on vertical axes and are arranged relative to the base 11 of the frame so that the base is supported in a position spaced from a curb 60 or other like element. In a typical situation, the apparatus is to be operated over a pavement P at one edge of which there is a curb 60, and in such case the supporting rollers hereinabove described rest on the pavement while the curb rollers 50 engage the face 61 of the curb.

In a preferred construction, the mounting for each curb roller 50 involves a connection between the roller and the frame which provides for adjustment of the roller relative to the frame. In the case illustrated, each roller 50 is supported by a stem 65 slidably carried in a guide 12 of the frame and the stem carries a yoke 66 in which the roller 50 is located, the roller being supported on a pivot 67 which is carried by the yoke. The stem 65 is preferably slidable and may be rotatable in its supporting brace and a suitable means such as a set screw 68 is provided for setting the stem in the desired position relative to the frame or supporting brace. Through the construction just described, the curb engaging rollers 50 can be adjusted to various positions relative to the frame to meet road or working conditions, as circumstances require. In a typical case or situation, the curb engaging rollers 50 will be set so that the base 11 of the frame is spaced but a short distance from the curb and is parallel therewith, in which case the body 10 of the frame is normal to the curb. If desired, however, the stems 65 of the mountings above described can be positioned so that the rollers 50 support the base 11 at various angles relative to the curb, or at various distances from the curb.

The marker E is shown as involving a marking element 70 and a carrier 71 supporting the element. In the particular case under consideration, the marking element 70 is an elongate body of chalk or the like and the carrier 71 is a tubular element in which the stick of chalk is slidably mounted. A suitable means, such as a helical compression spring 72, may be provided in the carrier 70 behind or at the inner end of the chalk so that the chalk is cushioned. This construction allows for shifting or variation of the chalk in the holder as the apparatus operates so that the chalk is maintained in proper marking engagement with the pavement P.

The means F supporting the marker from the

frame preferably provides for adjustment of the marker relative to the frame so that the angle or position of the marker relative to the pavement P can be adjusted and so that the spacing of the marker from the frame can be adjusted. In the form of the invention illustrated, the means F involves a rod 80 slidably carried by the frame and the rod carries the carrier 71 of the marker. In the case illustrated, the rod 80 is slidably engaged in the frame body 10 so that it can be shifted longitudinally therein or can be rotated therein as circumstances require. A suitable means is provided for setting the rod in suitable adjusted position. In the case illustrated, a releasable means in the form of a set screw 81 is provided for this purpose. The marker above described can be mounted on or secured to the rod 80 in any suitable manner. In the case illustrated, a collar 83 is provided on the marker, that is, on the carrier of the marker, and the collar 83 is slidable and rotatable on the rod 80. Through this construction, the marker can be slid along the rod to any desired position and can be rotated on the rod as desired. A suitable means such as a set screw 84 is provided for setting the collar in the desired position on the rod.

In the form of marker illustrated in Fig. 7, the carrier 71^a supports the collar 83 that receives the rod 80 and it has a lower arm 85 that carries the marking element 70^a and it has an upper arm 86 that carries a means for supplying material to the marking element. The marking element 70^a is in the form of a marking roller mounted on the arm 85 by a pivot pin 87. The means carried by arm 86 is adapted to supply marking material to the roller and is shown as including a container 88 carrying a suitable supply of marking material M and an applicator 89 that may be in the nature of a brush which receives material from the container and applies it to the roller. In the particular case illustrated the unit formed by the container 88 and the brush 89 is mounted on the arm 86 through a means 90 which provides for adjustment of this unit relative to the roller so that the desired contact or engagement may be maintained between the brush and the roller.

From the foregoing description it will be apparent that the invention provides a frame which is very simple in form and construction. The frame, together with the handle means C, may be a rigid or unitary structure formed entirely of tubing so that it is light and at the same time strong and durable. The supporting rollers of the means B are arranged or related to advantageously support the frame from or above the pavement P and by adjustment of the outer roller 30 the outer end portion of the frame can be adjusted relative to the pavement and thus vary the position of the marker-carrying portion of rod 80 above the pavement P. The guide means D is very simple in form and is highly effective in action. The curb engaging rollers can be adjusted as circumstances require and they are located so that they are spaced a substantial distance apart longitudinally of the curb and thus provide an effective guiding engagement between the device and the curb. In practice, the marker or markers that may be carried by the rod 80 can be readily set or adjusted to meet working conditions, and in the case shown in Fig. 1 the marker will provide an effective chalk mark 95 along the pavement P when the structure is operated along the pavement and in en-

gagement with the curb in the direction indicated by the arrow X in Fig. 1. When the marking means shown in Fig. 7 is employed the mark applied to the pavement may be in the nature of a painted line or mark which is more permanent than a chalk mark.

Having described typical preferred forms and applications of our invention, we do not wish to be limited or restricted to the specific details herein set forth, but wish to reserve to ourselves any variations or modifications that may appear to those skilled in the art and fall within the scope of the following claims.

Having described our invention, we claim:

15. 1. A marking device of the character described including, a flat horizontally disposed frame having a straight elongate tubular body and a straight base transverse of the body connected to the inner end thereof, a handle on the frame and projecting up therefrom, supporting wheels carried by and located beneath the base and spaced apart lengthwise of the base, a single supporting wheel carried by and located beneath the outer end portion of the frame, guide rollers in the plane of the frame at the ends of the base, an extensible rod slidably engaged in the body from the outer end thereof and projecting outwardly therefrom, means releasably setting the rod in adjusted relationship with respect to the frame, and a marker holder on the rod at the outer extremity thereof and adapted to carry a depending marking element.
20. 2. A marking device of the character described including, a flat horizontally disposed frame having a straight elongate body, a straight elongate base disposed transversely of the body at the inner end thereof and projecting equally in opposite directions therefrom, and tubular braces between the ends of the base and the body outward from the base, extensible stems slidably carried in the braces and projecting from the inner end of the frame, guide rollers on the stems, means releasably setting the stems in adjusted relationship with respect to the braces, supporting rollers depending from the frame, an extensible rod projecting from the outer end of the frame, and a marker holder carried by the rod and adapted to carry a marker so it depends from the outer end thereof.
25. 3. A marking device of the character described including, a flat horizontally disposed frame having a straight elongate tubular body, a straight base extending transversely of the body at the inner end thereof and projecting equally in opposite directions from the body, and tubular braces between the ends of the base and the body outward from the base, extensible stems slidably carried in the braces and projecting from the inner end of the frame, guide rollers on the stems, means releasably setting the stems in adjusted relationship with respect to the braces, supporting rollers depending from the frame, an extensible rod projecting from the outer end of the frame, and a marker holder carried by the rod and adapted to carry a marker so it depends therefrom.
30. 4. A marking device of the character described including, a flat horizontally disposed frame having a straight elongate body, a straight elongate base disposed transversely of the body at the inner end thereof and projecting equally in opposite directions from the body, and tubular braces between the ends of the base and the body out-

ward from the base, extensible stems slidably carried in the braces and projecting from the inner end of the frame, guide rollers on the stems, means releasably setting the stems in adjusted relationship with respect to the braces, supporting rollers depending from the frame, an extensible rod slidably carried in the body and projecting from the frame, and a marker holder carried by the rod and adapted to carry a marker so it depends therefrom, there being a supporting roller at each end of the base and a supporting roller at the outer end portion of the body, the supporting roller at the outer end portion of the body being adjustable vertically of the frame.

5. A marking device of the character described including, a flat horizontally disposed frame having a straight elongate tubular body and a straight elongate base disposed transversely of the body at the inner end thereof and projecting equally in opposite directions from the body, a handle on the frame, projecting up therefrom, supporting wheels carried by and located beneath the base and spaced apart lengthwise thereof, a single supporting wheel beneath the outer end portion of the frame, guide rollers at the ends of the base, an extensible rod slidably engaged in the body from the outer end thereof and projecting outwardly therefrom, means releasably setting the rod in adjusted relationship with respect to the frame, a marker holder, and means mounting the holder on the rod for adjustment around and along the rod, and a member releasably setting the holder in adjusted relationship with respect to the rod.

6. A marking device of the character described including, a flat horizontally disposed frame having a straight elongate tubular body and a straight elongate base transverse of the body at the inner end thereof and projecting equal distances in opposite directions from the body, a handle on the frame, supporting wheels spaced apart beneath the base, a single supporting wheel beneath the outer end portion of the frame, guide rollers at the ends of the base, an extensible rod slidably engaged in the body from the outer end thereof and projecting outwardly therefrom, means releasably setting the rod in adjusted relationship with respect to the frame, and a marker holder adapted to carry a marking element and including a carrier supporting the element, a collar on the carrier passing the rod, and means releasably setting the collar in adjusted relationship with respect to the rod.

7. A marking device of the character described including, a frame having an elongate tubular body and a base transverse of the body at the inner end thereof, a handle on the frame, supporting wheels spaced apart beneath the base, a single supporting wheel beneath the outer end portion of the frame, guide rollers at the ends of the base, an extensible rod slidably engaged in the body from the outer end thereof and projecting outwardly therefrom, means releasably setting the rod in adjusted relationship with respect to the frame, and a marker holder on the rod and adapted to carry a marking element, the single supporting roller including a mounting having a collar on the body, and a roller carrying arm projecting from the collar.

8. A marking device of the character described including, a frame having an elongate tubular body and a base transverse of the body at the inner end thereof, a handle on the frame, supporting wheels spaced apart beneath the base, a

single supporting wheel beneath the outer end portion of the frame, guide rollers at the ends of the base, an extensible rod slidably engaged in the body from the outer end thereof and projecting outwardly therefrom, means releasably setting the rod in adjusted relationship with respect to the frame, and a marker holder on the rod and adapted to carry a marking element, the single supporting roller including a mounting having a collar on the body, means releasably setting the collar in adjusted rotative relationship with respect to the body, and a roller carrying arm projecting from the collar.

9. A marking device of the character described including, a flat horizontally disposed frame having a straight elongate tubular body and a straight elongate base transverse of the body at the inner end thereof and projecting equally in opposite directions therefrom, a handle on the frame, supporting wheels spaced apart beneath the base, a single supporting wheel beneath the outer end portion of the frame, guide rollers at the ends of the base, an extensible rod slidably engaged in the body from the outer end thereof and projecting outwardly therefrom, means releasably setting the rod in adjusted relationship with respect to the frame, and a marker including a marking element, a carrier supporting the element, a collar on the carrier passing the rod, and means releasably setting the collar in adjusted relationship with respect to the rod, the marking element including a roller, a container carrying a supply of marking material, and an applicator receiving material from the container and applying it to the roller.

10. A marking device of the character described including, a frame having an elongate tubular body, a base at the inner end of the body and transverse thereof, elongate tubular braces from the ends of the base to the body at a point spaced from the base, brackets depending from the end portions of the base, supporting rollers carried by the brackets, a collar rotatably carried on the body outward of the braces, means releasably setting the collar in adjusted rotative relationship with respect to the frame, an arm projecting from the collar, a supporting roller carried by the arm, extensible stems slidably carried in the braces and projecting from the frame, means releasably setting the stems in adjusted relationship with respect to the frame, guide rollers carried by the stems, an extensible rod slidably carried in the body and projecting from the outer end thereof, means releasably setting the rod in adjusted relationship with respect to the frame, a marker holder carried by the rod, and a handle projecting from the frame.

11. A marking device of the character described including, a frame having an elongate tubular body, a base at the inner end of the body and transverse thereof, elongate tubular braces from the ends of the base to the body at a point spaced from the base, brackets depending from the end portions of the base, supporting rollers carried by the brackets, a collar rotatably carried on the body outward of the braces, means releasably setting the collar in adjusted rotative relationship with respect to the frame, an arm projecting from the collar, a supporting roller carried by the arm, extensible stems slidably carried in the braces and projecting from the frame, means releasably setting the stems in adjusted relationship with respect to the frame, guide rollers carried by the stems, an extensible rod slidably carried in the body and projecting from

the outer end thereof, means releasably setting the rod in adjusted relationship with respect to the frame, a marker holder carried by the rod, the marker holder including a collar slidably carried on the rod, means releasably setting the last mentioned collar in adjusted relationship with respect to the rod, and a handle projecting from the frame.

12. A marking device of the character described including, a flat horizontally disposed frame having a straight elongate tubular body, a straight elongate base at the inner end of the body and extending transversely thereof and projecting equally in opposite directions therefrom, elongate tubular braces from the ends of the base to the body at a point spaced from the base, brackets depending from the end portions of the base, supporting rollers carried by the brackets, a collar on the body outward of the braces, means releasably setting the collar against movement relative to the frame, an arm projecting from the collar, a supporting roller carried by the arm, stems carried in the braces and projecting from the frame, means releasably setting the stems against movement relative to the frame, guide rollers carried by the stems, a rod carried in the body and projecting from the outer end thereof, means releasably setting the rod against

movement relative to the frame, a marker carried by the rod, the marker including a collar on the rod, means releasably setting the last mentioned collar against movement relative to the rod, and a handle projecting from the frame, the marker including a marking roller, a container to carry marking material, and an applicator adapted to receive material from the container and apply it to the marking roller.
